DESIGN FOR A HOUSE COAT OR SIMILAR ARTICLE

Marie F. Hauck, Chicago, Ill., assignor to Walter M. Gotsch Company, Chicago, Ill., a corporation of Illinois

Application February 26, 1940, Serial No. 90,536

Term of patent 3½ years

To all whom it may concern:

Be it known that I, Marie F. Hauck, a citizen of the United States, residing at Chicago, in the county of Cook and State of Illinois, have invented a new, original, and ornamental Design for a House Coat or Similar Article, of which the following is a specification, reference being had to the accompanying drawing, forming part thereof.

In the drawing, Fig. 1 is a front view of a house coat showing my design, and Fig. 2 is a rear view thereof on a slightly smaller scale.

I claim:

The ornamental design for a house coat or similar article, as shown.

MARIE F. HAUCK.
